Specification for Design.

Patented Nov. 2, 1915.

Application filed May 18, 1915. Serial No. 28,979. Term of patent 14 years.

To all whom it may concern:

Be it known that I, CLARENCE E. SMITH, a citizen of the United States, residing at New Britain, Hartford county, Connecticut, have invented a new, original, and ornamental Design for a Fastener Member for Bags and Suitcases, of which the following is a specification, reference being had to the accompanying drawing, forming a part thereof, in which—

Figure 1 is a front elevation of my new,

original and ornamental fastener member on a relatively enlarged scale. Fig. 2 is an edge view thereof looking from left to right.

I claim:

The ornamental design for a fastener member for bags and suitcases as shown.

CLARENCE E. SMITH.
